HEAD FOR CLAMSHELL BUCKETS

Edward L. Harrington, Pittsburgh, Pa., assignor to
 Blaw-Knox Company, Pittsburgh, Pa., a corporation of New Jersey

Application August 24, 1938, Serial No. 226,496

5 Claims. (Cl. 37—183)

This invention relates to a head assembly for clamshell buckets and the like provided with a holding line or cable and a closing line or cable by which the bucket, when held in fixed position by the holding line, may be opened or closed to pick up or discharge material.

It has been the practice heretofore in constructing buckets of this type to provide guide rollers to protect the closing line from wear by chafing in the event that the bucket is tilted sidewise on being lowered onto a pile of material to pick up a load therefrom. These guide rollers also protect the closing line in case of endwise tipping of the bucket. The arrangement of guide rollers used heretofore is satisfactory for such work as handling material from stock piles or open deck barges. When such buckets are used for unloading material from a ship's hold, however, it is found that the previous arrangement of guide rollers does not prevent chafing of the closing line. This appears to be the result of the fact that the bucket is tipped endwise in one direction or the other as it is lowered onto the material. While there is little or no tendency for the bucket to tilt sidewise, because of the concavity formed in the top of the pile by the removal of material substantially from the center thereof, there is a decided tendency for the bucket to tip endwise as it almost invariably lands on the sloping sides of the depression.

I have invented a novel form of head assembly for buckets intended for use in such applications as that mentioned above where endwise tipping of the bucket is practically inevitable, with little or no sidewise tipping as the bucket is lowered. In a preferred form of the invention, I provide a head casting having elongated guide rollers journaled therein in such manner that their axes lie in a plane at an angle to the horizontal when the bucket is suspended. I also provide a plurality of auxiliary guide rollers journaled in the casting in vertically spaced relation in such position that they are adapted to be engaged by the closing line when the latter emerges at an angle to its normal position because of endwise tipping of the bucket. The invention will be described in greater detail by reference to the accompanying drawing illustrating a preferred embodiment. In the drawing:

Fig. 1 is a side elevation of the upper portion of a clamshell bucket, with parts omitted for clearness;

Fig. 2 is an end view of the structure shown

in Fig. 1 such as would be seen by looking from the right in the latter; and

Fig. 3 is a plan view.

Referring now in detail to the drawing, the head assembly of my invention includes a main casting 10 which is a box-like structure having end walls 11 and 12 and side walls 13 and 14. A pin 15 is journaled transversely in the casting and is adapted to be engaged by an eye (not shown) to which the holding line or cable is secured.

The bucket halves (not shown) are secured to corner bars 16 and 17. The bars 16 are secured to plates 18 which are in turn secured to the side walls 13 and 14 of the casting 10 as by rivets, bolts or the like. A hinge pin 19 extends through eyes formed at the upper ends of the corner bars 17 and also through the plates 18 and provides a hinge bearing for the corner bars 16. Sheaves 20 are journaled on the pin 19 between the eyes of the corner bars 16. Cooperating sheaves 21 are journaled on a shaft 22. The shaft 22 is supported in suitable bearings 23 secured to lever arms 24 pivoted together at 25. While the invention has been illustrated in connection with a lever arm type of bucket, it will be understood that it is also applicable to buckets of other types.

The closing line as indicated at 26 is reeved about the sheaves 20 and 21 and is dead-ended in a socket 27 formed in the main casting 10.

The closing line 26 extends upwardly from one of the sheaves 20 between guide rollers 28 journaled in the end walls 11 and 12 of the casting 10. As shown in Figs. 1 and 2, the guide rollers 28 are so mounted in the casting 10 that their axes lie in a plane inclined to the horizontal when the bucket is closed and suspended in normal position. The rollers 28 are substantially tangent to the sheaves 20 when viewed in elevation and are long enough to extend on both sides of the point of tangency. The angular position of the rollers permits them to function as desired without being excessively long. Lips 29 and 30 are formed in the end walls 11 and 12 to receive the closing line on tilting of the bucket endwise to an extent such that the closing line assumes the position indicated in dotted lines at 31 relative to the casting 10. It will be understood, of course, that the closing line is always vertical and that the bucket tips endwise through the angle indicated by the dotted line position 31 of the closing line. On tipping in the other direction, the closing line may assume the position shown in dotted line at 32 relative to the

head assembly. Auxiliary rollers 33 are journaled transversely in the casting 10, in vertically spaced relation and in such position as to be engaged by the closing line 26 on tilting of the bucket such that the closing line moves to the position indicated at 31 relative to the head assembly. The use of a plurality of rollers 33 also aids in obtaining the desired operation without making the rollers 28 of greater length.

10 As already stated, the bucket is subjected to endwise tipping continuously when unloading material from a walled chamber such as the hold of a ship, because of the concave depression formed in the top of the mass as material is removed therefrom.

It will be observed by reference to Fig. 1 that when the head assembly tilts to the left so that the relative position of the closing line is that indicated at 31, there is relatively little opportunity for chafing of the closing line since it crosses the rollers 28 substantially at right angles thereto. At the same time, the auxiliary rollers 33 prevent the formation of sharp bends in the cable and thus further protect it from excessive wear. When the bucket tips endwise in the opposite direction so that the relative position of the closing line is that indicated at 32, it will be observed that the closing line is protected against undesirable chafing by the fact that it wraps around the sheave 20 to a greater extent so that the flanges thereof have the effect of centering the cable between the rollers 28. The radius of the sheave, furthermore, is such that the formation of sharp bends and the like is precluded.

As shown, the pin 15 to which the hold line is secured, is laterally spaced from the pivot pin 19. This permits endwise tilting of the bucket to a considerable angle before the closing line 26 engages the lip 30. The angle of permissible tilting is thus not limited by engagement of the line 26 with the hold line anchorage as in former constructions.

The principal advantage of the construction described and illustrated herein is the avoidance of the chafing of the closing line on the guide rollers such as has been experienced in buckets as previously constructed. By avoiding sharp bends and chafing of the line on the guide rollers, excessive wear is eliminated and the life of the cable considerably extended. The seriousness of the problem which is overcome by the invention may readily be realized from the fact that the closing of the bucket requires the overhauling of from twenty to over thirty feet of closing line, depending upon the manner of reeving or the number of sheaves employed. Rapid wear of this length of cable involves quite an item of expense which is largely obviated by the present invention.

Instead of using rollers 28 to guide the closing line, I may form rounded guiding edges integral with the casting 10 and dispense with the rollers.

Although I have illustrated and described but one preferred embodiment of the invention, it will be appreciated that changes therein may be made without departing from the spirit of the invention as set forth in the appended claims.

I claim:

70 1. A head for a clamshell bucket comprising a main casting, corner bars hinged on a com-

mon pin, means supporting the pin on the casting, a closing line reeved about sheaves journaled on said pin, guide rollers so journaled on said casting that their axes are at a substantial angle to the horizontal when the bucket is closed and suspended, and an anchorage for a holding line, said anchorage and the greater portion of said rollers being on opposite sides of said pin.

2. A head for a clamshell bucket comprising a main casting, corner bars to which the bucket halves are secured, a hinge pin on which the corner bars are pivoted, a closing line reeved about sheaves on the pin and on a relatively movable part of the bucket, and guide rollers journaled in said casting for confining said line, said rollers being substantially tangent to said sheaves in side elevation, extending on both sides of the point of tangency and so disposed that their axes are inclined at a substantial angle to the horizontal when the bucket is closed and suspended.

3. A head for a clamshell bucket comprising a main casting, corner bars to which the bucket halves are secured, a hinge pin on which the corner bars are pivoted, a closing line reeved about sheaves journaled on said pin, and guide rollers so journaled on said casting that their axes are at a substantial angle to the horizontal when the bucket is closed and suspended, the rollers being substantially tangent to said sheaves in side elevation, extending on both sides of the point of tangency and having their lower ends on that side of said sheaves which the closing line last departs from, on being taken in.

4. A head for an openable lifting bucket comprising a casting, means thereon whereby the bucket may be suspended, corner bars secured to the bucket halves and hinged on a common pivot pin, sheaves on said pin, and a guide throat above said pin, the edges of said throat being substantially tangent to said sheaves in side elevation, extending on both sides of the point of tangency and inclined at a substantial angle to the horizontal when the bucket is closed and suspended, whereby to confine a closing line reeved about said sheaves and extending outwardly through said throat, said suspending means and the greater portion of said throat being on opposite sides of said pin.

5. A head for a clamshell bucket comprising a main casting, corner bars to which the bucket halves are secured, a hinge pin on which the corner bars are pivoted, a closing line reeved about sheaves on the pin and on a relatively movable part of the bucket, guide rollers journaled in said casting for confining said line, said rollers being substantially tangent to said sheaves in side elevation, extending on both sides of the point of tangency and so disposed that their axes are inclined at a substantial angle to the horizontal when the bucket is closed and suspended, and a plurality of horizontal guide rollers journaled in said casting in vertically spaced relation below the lower ends of said first-mentioned rollers and adapted to be engaged by the closing line on tipping of the bucket in such direction that the line tends to depart from one of said sheaves which it normally engages.
